UNITED STATES PATENT OFFICE.

EDWARD G. ERVIN, OF KANSAS CITY, MISSOURI.

BURGLAR-ALARM.

1,285,961.

Specification of Letters Patent. Patented Nov. 26, 1918.

Application filed February 12, 1918. Serial No. 217,269.

To all whom it may concern:

Be it known that I, EDWARD G. ERVIN, a citizen of the United States, residing at Kansas City, in the county of Jackson and State 5 of Missouri, have invented certain new and useful Improvements in Burglar-Alarms of which the following is a specification.

This invention relates to burglar alarms, and more especially to devices of this character adapted for use in connection with doors and windows, and the object of the invention is to produce a burglar alarm of simple, strong, durable and cheap construction to be held cocked for action by a closed 10 door or window and to operate automatically the instant the door or window is slightly opened.

More specifically my object is to produce a device of the character set forth, composed 20 of a base plate, and a single operative part or hammer, the latter to make its operative stroke under the power of a spring held under tension only when the hammer and one end of the plate are interposed between 25 a fixed part of a door or window casing and the closed door or window respectively.

With the object of producing a burglar alarm of the character set forth, the invention consists in certain novel and useful features 30 of construction and combinations of parts as hereinafter described and claimed; and in order that it may be fully understood, reference is to be had to the accompanying drawing, in which:—

35 Fig. 1, is a fragmentary horizontal section of a door and door casing with a burglar alarm embodying my invention, arranged in operative relation thereto.

Fig. 2, is a view disclosing one face of the 40 device, and showing the latter in operative relation to the door, and its hammer in cocked position in full lines and in explosion position in dotted lines.

Fig. 3, is a vertical section of part of a 45 window casing with the burglar alarm in operative position relative to the window casing and sash.

Referring to the drawing in detail, 1 indicates a metal plate preferably tapered at its 50 ends and of such size as to be conveniently carried in a purse or vest pocket, and provided nearer one end than the other with one or more prongs 2 standing out from one of its faces, the prong or prongs constituting a 55 shoulder in the use of the device on a door or the like, as hereinafter explained.

At the end of the plate most remote from the said prongs, are formed clips 3 for holding flatly against the opposite side of the plate from said prongs, a percussion cap 4, or 60 equivalent device for sounding an alarm, preferably in similitude of that produced by firing a revolver or the like, so as to not only awaken the household but frighten the person attempting the unauthorized entrance. 65

About midway between the prongs and clips, the plate is provided with a pair of ears 5, disposed at right angles to the prongs and at the same side of the plate as said clips.

A hammer for striking and exploding the 70 percussion cap or the like, is pivoted to the ears 5. It is preferably formed of wire bent to provide a pivot 6 extending through said ears, and an arm 7 in the form of a loop narrowed or attenuated at its free end so 75 that it may pass between the clips and impinge upon the central portion of the cap. The parts are so proportioned that the hammer when in cocked position, converges slightly with respect to the plate against 80 which it bears at its free end, so as to facilitate the fitting of the said end and the proximate part of the plate in the narrow space usually found between a door and its jamb or a window sash and the sill stop or sill 85 shoulder of a window casing.

To effect operation of the hammer, a spring is provided, the same being preferably produced by doubling it to provide the alined coils 8, the loop end 9 between said 90 coils and the free ends 10, at the outer ends of the coils. The coils fit upon the pivot 6 of the hammer, with the loop end 9 bearing against the plate and the free ends or terminals 10 bearing against the hammer and 95 tending to hold it in or throw it to the position shown by dotted lines in Fig. 2.

In Fig. 1, 11 indicates a door jamb, 12 the door stop, 13 the trim at the inner side of the jamb, and 14 the door for closing adjacent 100 the jamb and against the stop, the space between the jamb and free edge of the door accommodating the free end of the hammer 7 and one end of the plate 1, the latter being slipped into said space until the prongs or 105 shoulder engage the inner face of the door, at which time the hammer actuating spring applies sufficient power to hold or maintain the plate and hammer in place until the door is opened sufficiently to effect withdrawal of 110 the hammer from engagement with the jamb, it being noted that this withdrawal action is

positive as the prongs or shoulder occupy the path of inward movement of the door. The instant the door is opened to the degree mentioned, the spring effects operation of the 5 hammer and the device falls to the floor, the explosion being practically simultaneous with the fall.

Where the device is used on a window, the prongs are embedded in the lower sash at 10 the inner side thereof, with the plate so arranged that it and the hammer when in cocked position, shall be interposed between the sash and sill shoulder or stop when the sash is closed, and shall be withdrawn from 15 such position when the sash is lifted high enough to cause the hammer to clear the said shoulder. In Fig. 3, 15 indicates the sill having a shoulder 16 supplemented by a sill stop 17, the sash 18, being spaced from the 20 shoulder far enough to accommodate the device, as shown.

From the above description, it will be ap-

parent that I have produced a burglar alarm embodying the features enumerated as desirable in the statement of the object of the 25 invention, and it is to be understood that I reserve the right to make all changes properly falling within the spirit and scope of the appended claim.

I claim:

A burglar alarm comprising a plate having laterally-projecting prongs at an intermediate point, oppositely-projecting ears at another point and standing at right angles to said prongs, and clips for holding sound-producing means, and a hammer pivoted to said ears to stand either adjacent said clips or said prongs, and a spring mounted on said hammer at its pivoted end and bearing against said plate and hammer to swing the latter 40 from its position near the prongs to its position near said clips.

In testimony whereof I affix my signature.
EDWARD G. ERVIN.
